FOLDING WASHBASIN PROVIDED WITH
ARTICLE INTERCEPTING PLATE

Harry Alfred Bunker, St. Lambert, Quebec, Canada, assignor to The Robert Mitchell Company Limited, Montreal, Quebec, Canada

Application January 26, 1949, Serial No. 72,987

4 Claims. (Cl. 4—169)

1

This invention relates to folding wash basin installations of the type in which the wash basin is mounted to swing about a horizontal axis from a vertical position within a wash basin cabinet to a horizontal position in which the wash basin is disposed exteriorly of the cabinet.

A disadvantage inherent in conventional folding wash basin installations of the type to which this invention relates is that when the basin is swung upwardly to its vertical out-of-the-way position within the basin cabinet any objects which have inadvertently been left in the basin by the user will drop out of the basin to inaccessible positions in the lower portion of the cabinet enclosing the basin and its plumbing connections. With this in mind the primary object of the present invention is to provide a generally improved folding wash basin of the type referred to in which the basin is equipped with an article retaining attachment which, when the basin is swung to its vertical out-of-the-way position within the basin cabinet, serves to intercept and support any articles which drop from the basin so that said articles may be readily retrieved when the basin is swung out of the basin cabinet to its horizontal position of use.

Other objects, advantages and characteristic features of the invention will be more readily understood from the following detailed description of the accompanying drawings, in which—

Fig. 1 is a vertical sectional view of a folding wash basin installation embodying my invention. In this view the wash basin is shown swung to its vertical, out-of-the-way position within the wash basin cabinet.

Fig. 2 is a view similar to Fig. 1 but showing the wash basin swung to a horizontal position projecting outwardly from the wash basin cabinet.

Fig. 3 is a detail sectional view taken substantially along the line 3—3 of Fig. 2.

Referring more particularly to the drawings, 5 designates a wash basin cabinet presenting a wash basin receiving compartment 6 defined by a top wall 7, a rear wall 8 and side walls 9 and having a front opening 10. The portion of the cabinet which lies below the opening 10 serves as an enclosure for the wash basin plumbing connections which are not shown herein since these connections form no part of the invention and may be made in accordance with conventional practice.

A wash basin supporting and enclosing casing 12 is mounted to swing about a horizontal axis

2

so that it may be swung to a vertical out-of-the-way position within the wash basin compartment 6 as shown in Fig. 1, or to a horizontal position extending outwardly from the lower portion of said compartment as shown in Fig. 2. The casing 12 comprises a top wall 13, a bottom wall 14, a front wall 15 and side walls 16. The top wall 13 is provided with an opening 17 beneath which a wash basin 18 is positioned the rim of the basin being secured in any suitable manner to that portion of the top wall 13 of casing 12 which borders the opening 17.

The wash basin supporting casing 12 is carried by a pair of swinging brackets 19 only one of 15 which is shown in the drawings. These brackets 19 are arranged close to the opposite side walls 16 of casing 12 and have their upper ends secured in any suitable manner to that portion of the top wall 13 of casing 12 which lies rearwardly 20 of basin 18. The lower portion of each bracket 19 is fastened by a pivot 20 to a stationary bracket 21 mounted on a suitable support 22 arranged in the wash basin cabinet 5 adjacent the lower portion of front opening 10 of basin compartment 25 6. The pivots 20 provide a horizontal axis about which the wash basin 18 and its supporting casing 12 are swingable from the position shown in Fig. 1 to the position shown in Fig. 2 and vice versa.

When the wash basin 18 is in the vertical position shown in Fig. 1 it will be obvious that, in the absence of any preventive means, articles which have inadvertently been left in the basin will fall therefrom and drop to an inaccessible position among the plumbing connections or other obstructions housed in that portion of cabinet 5 which lies below the wash basin compartment 6. In order to overcome this difficulty I provide an article intercepting plate 24 having 35 its lower edge fastened to the rear edge of the top wall 13 of the basin supporting casing 12 by a suitable hinge 25. The upper edge of plate 24 is rolled to provide a tube 26 containing a rod 27 (Fig. 3) which is fixed in the central portion of the tube and terminates in spaced 45 relation to the ends of the tube. A pair of spring projected guide pins 28 are slidably fitted in the ends of tube 26 and are partially projected therefrom by means of coiled compressed springs 50 29 interposed between the inner ends of the guide pins and the adjacent ends of the fixed rod 27. As shown to advantage in Fig. 3 the guide pins 28 extend outwardly through vertical slots 31 provided in the side walls 9 of basin compartment 6 and are received in vertically extending

channel guides 32 which are secured to the walls 9 over said slots. As here shown each channel guide 32 comprises a flat portion 33 secured to the outer surface of one of the side walls 9 of basin compartment 6 and having a portion 34 thereof bent into U-form to provide an inwardly facing channel guide covering one of the slots 31. The springs 29 acting against the guide pins 28 serve to urge them against the bottoms of the channel guides to prevent rattling.

When basin 18 and its supporting casing 12 are swung from the horizontal position shown in Fig. 2 to the vertical position shown in Fig. 1 the lower hingedly connected edge of the article intercepting plate 24 travels downwardly along the arcuate path X (Fig. 2) to the position X' (Fig. 1) and, at the same time, the upper rolled edge of plate 24 travels downwardly along the guide channels 34 to the position indicated at X² in Fig. 1. Since the plate 24 extends substantially the full width of the wash basin compartment 7 it will be seen that any articles dropping from the basin in the vertical position thereof will be intercepted and held by the plate 24 so that such articles can easily be retrieved when the basin 18 and the plate 24 are returned to the position shown in Fig. 2.

Having thus described the nature of my invention and a preferred embodiment thereof it will be understood that various modifications may be resorted to within the scope and spirit of the appended claims.

The embodiments of this invention in which an exclusive property or privilege is claimed are defined as follows:

1. A wash basin installation comprising a cabinet having a wash basin receiving compartment, a wash basin, means mounting said wash basin for swinging movement about a horizontal axis from a horizontal position in which the wash basin is disposed exteriorly of said compartment to a vertical position in which the wash basin is housed within said compartment, an article intercepting plate movable with the wash basin and adapted to intercept and support articles dropping from the wash basin when the latter is swung to its vertical position within said compartment, means hingedly connecting the lower edge of said plate to said wash basin, the side walls of said compartment being provided with opposed inwardly opening guide channels extend-

ing in a vertical direction and located immediately adjacent the rear wall of said compartment and plate guiding elements projecting into said channels from opposite ends of the upper edge portion of said plate.

2. A wash basin installation as set forth in claim 1, in which said guide projections are slidably supported by said plate and are spring projected into said channels.

3. A wash basin installation as set forth in claim 1, in which the plate is provided with a tubular upper edge portion and in which said guide projections are slidably mounted in said tubular portion and are spring projected into contact with the bottom walls of said channels by springs arranged in the tubular portion of said plate and acting outwardly against said guide projections.

4. A wash basin installation comprising a cabinet having an open-front wash basin receiving compartment bounded by top, side and rear walls, the side walls being provided with elongated, vertically extending slots located immediately adjacent the rear wall, and separately formed channel members secured to the outer surfaces of the side walls of said compartment over said slots to provide opposed inwardly opening guide channels, a wash basin, means mounting said wash basin for swinging movement about a horizontal axis located in the lower portion of said compartment, said wash basin being swingable about said axis from a horizontal position disposed exteriorly of said compartment to a vertical position in which the wash basin is housed within said compartment, an article intercepting plate adapted to intercept and support articles dropping from the wash basin when the latter is swung to its vertical position within said compartment, means hingedly connecting the lower edge of said plate to said basin and guide projections extending outwardly from opposite ends of the upper edge of the plate and into the slots and guide channels of the side walls of the compartment.
